AUTOMATIC SPLITTING MACHINE

Irving C. Finkelstein, Brooklyn, N. Y.

Application November 3, 1945, Serial No. 626,529

7 Claims. (Cl. 164—60)

1

This invention relates to new and useful improvements in an automatic splitting machine.

The splitting machines heretofore known essentially consisted of a table and means for drawing a web of goods longitudinally thereof. In this type of splitting machine it is general to manually hold a pair of shears or other cutter against the moving goods for splitting the same.

This invention proposes an automatic machine for splitting goods which is capable of splitting the goods to selected widths.

More particularly, the new and improved splitting machine is characterized by the provision of a rod transversely mounted of the table, a platform extending longitudinally of the table and adjustably mounted on said rod, and a motor driven disc cutter associated with said platform to do the actual splitting. With this arrangement it is possible to shift the platform right and left, as desired for controlling the width of the pieces split from the web of goods.

Still further the invention proposes a simple arrangement by which the cutter disc may be easily sharpened.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a front elevational view of an automatic splitting machine constructed in accordance with this invention.

Fig. 2 is a vertical sectional view taken on the line 2—2 of Fig. 1.

Fig. 3 is a fragmentary enlarged horizontal view looking in the direction of the line 3—3 of Fig. 2.

Fig. 4 is a vertical sectional view taken on the line 4—4 of Fig. 3, the section through certain of the parts being shifted to better illustrate the device.

Fig. 5 is a fragmentary sectional view taken on the line 5—5 of Fig. 4.

The automatic splitting machine, in accordance with this invention, includes a table 10 provided with means for drawing a web of goods longitudinally thereof. This means includes a vertical frame 11 mounted on the rear of the table 10 and rotatively supporting a friction drum 12.

2

A pulley 13 is connected with the friction drum 12 and is engaged by a belt 14. This belt 14 extends downwards along the side of the frame 11 and engages over another pulley 15 which is connected with a shaft 16 provided with still another pulley 17. This latter pulley 17 is connected by a belt 18 to a drive pulley 19. The drive pulley 19 is mounted upon a shaft 20 and controlled with a clutch 21. The clutch 21 is operated by an adjustable arm 22 which connects with one end of a foot bar 23. The bar 23 is pivotally mounted at its other end upon a pintle 24 mounted on the bottom of the table 10. The shaft 20 is driven by a pulley 20' engaged by a belt 29 which is connected with the pulley 25 of an electric motor 26 mounted beneath the table 10.

The goods schematically illustrated by the dot and dash lines 27 comes up over the front edge of the table 10, then passes over the top of the table and under a rod 28 which is mounted across the bottom of the frame 11. From this rod 28 the goods pass up over the friction drum 12 and then down to a receiving point.

Up to here the splitting table is more or less conventional. It now departs in the provision of a rod 30 transversely mounted of the table 10, and more specifically, across the bottom of the frame 11. A platform 31 extends longitudinally of said table 10 and is adjustably mounted on the rod 30. The platform 31 is formed from a sheet metal piece. It has a top wall 32 and a skirt wall 33 around the edges of the top wall 32. The rod 30 passes through the side sections of the skirt wall 33. Collars 34 are slidably mounted on the rod 30 and engage the sides of the skirt wall 33 for holding the platform 31 in selected adjusted positions upon the rod 30. Wing screws 35 threadedly engage through the collars 34 and abut the rod 30 for holding said collars as desired.

A cutter foot 36 is mounted upon the bottom of the platform 31 and rests upon the top of the table 10. This cutter foot 36 has a flat bottom portion 37 which is provided with a piece of felt 45 38 or other padding on its bottom face, so that when resting on the table 10 it does not damage the surface of the table. The flat bottom portion 37 is rigidly connected with a very thin vertical back portion 39 having a knife-like front edge 40. This back portion 39 connects with a top bracket 41 which is attached upon the bottom face of the top wall 32 of the platform 31.

A cutter disc 42 is rotatively mounted above the cutter foot 36, and more particularly, above 55 the flat bottom portion 37 thereof. The cutter

disc 42 is fixedly mounted on a shaft 43 which is provided with ball bearings 44 mounted in a pair of tubes 45 located to the sides of the cutter disc 42. These tubes 45 are removably attached to the bracket 41 by several fastening screws 46. The shaft 43 is provided with a pulley 47 which is engaged by a belt 48 engaging the drive pulley 49 of an electric motor 50 mounted on the top face of the platform 31. A belt guard 51 is attached to the side of the skirt wall 33 of the platform 31 and engages over the belt 48 and the pulleys 47 and 49.

The flat bottom portion 37 of the cutter foot 36 is provided with a slot 52 into which the bottom portion of the cutter disc 42 engages. The goods schematically indicated by the dot and dash lines 27 pass over the top face of the flat bottom portion 37 so as to be split by the rotating cutter disc 42. The platform 31 is provided with a slot 53 in its top wall through which the top portion of the cutter disc 32 passes. A sharpener wheel 54 is rotatively mounted on an arm 55 which is mounted on a shaft 56 turnably mounted in a pair of standards 57 mounted upon the top of the platform 31. The shaft 56 is provided with a projecting handle 58 by which it may be moved. When the sharpener wheel 54 extends rearwards it is in an inoperative position. It may be engaged against the cutter disc 42 by moving the handle 58 so as to swing the arm 55 forwards, as indicated in Fig. 4 by the dot and dash lines.

The operation of the splitting machine is as follows:

When the clutch 21 is open, rotations of the electric motor 26 will not be transmitted to drive the means for drawing the web of goods, indicated by the dot and dash lines 27, longitudinally of the table 10. The operator may step on the bar 23 which depresses same and through the medium of the rod 22 indirectly closes the clutch 21. The clutch 21 is associated with the usual spring, not illustrated, which normally urges it open, when the rod 23 is released. When the clutch 21 is closed rotations from the motor 26 will be transmitted to rotate the friction drum 12, so that the web of goods is drawn rearwards across the table 10, as indicated by the same directional arrows in Fig. 2.

The cutter disc 42 is continuously being driven by the electric motor 50. The web of goods passing over the flat bottom portion 37 of the cutter foot 36 will be split by the rotating cutter disc 42. The split webs of goods will continue to pass under the rod 28 and over the friction drum 12.

The line of splitting may be varied by loosening the wing screws 35 so that the collars 34 are loosened. Now the front of the platform 31 may be manually gripped and the platform 31 swung slightly upwards so as to disengage the cutter foot 36 from the top of the table 10. It is now possible to shift the platform 31 laterally in one direction or the other any amount for determining the width of the splitting of the goods. When a desirable position is reached the platform 31 is released so that the flat bottom portion 37 comes to rest on the top of the table 10. The collars 34 are then placed adjacent the sides of the skirt wall 33 of the platform 31 and the wing screws 35 are retightened. A web of goods may then be engaged against the disc cutter 42 and then passed under the rod 28 and over the friction drum 12, and the machine is again ready to operate automatically.

While I have illustrated and described the pre-

ferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

- 10 1. An automatic splitting machine, comprising a table, means for guiding a web of goods longitudinally of said table, a rod transversely mounted of said table, a platform extending longitudinally of said table and adjustably mounted on 15 said rod, a cutter foot mounted on the bottom of said platform and resting on said table, a cutter disc rotatively mounted above said cutter foot, an electric motor mounted on said platform, and a transmission from said motor to said cutter disc.
- 20 2. An automatic splitting machine, comprising a table, means for guiding a web of goods longitudinally of said table, a rod transversely mounted of said table, a platform extending longitudinally of said table and adjustably mounted on 25 said rod, a cutter foot mounted on the bottom of said platform and resting on said table, a cutter disc rotatively mounted above said cutter foot, an electric motor mounted on said platform, and a transmission from said motor to said cutter disc, 30 said platform having a top wall and skirt walls, and said rod being engaged through said skirt wall.
- 35 3. An automatic splitting machine, comprising a table, means for guiding a web of goods longitudinally of said table, a rod transversely mounted of said table, a platform extending longitudinally of said table and adjustably mounted on said rod, a cutter foot mounted on the bottom of said platform and resting on said table, a cutter disc 40 rotatively mounted above said cutter foot, an electric motor mounted on said platform, a transmission from said motor to said cutter disc, and collars adjustably mounted on said rod and engaging the sides of said skirt wall.
- 45 4. An automatic splitting machine, comprising a table, means for guiding a web of goods longitudinally of said table, a rod transversely mounted of said table, a platform extending longitudinally of said table and adjustably mounted on 50 said rod, a cutter foot mounted on the bottom of said platform and resting on said table, a cutter disc rotatively mounted above said cutter foot, an electric motor mounted on said platform, and a transmission from said motor to said cutter disc,
- 55 55. said cutter foot having a flat bottom portion for resting on said table, and a vertical thin back portion connection with said bottom portion for supporting same.
- 60 5. An automatic splitting machine, comprising a table, means for guiding a web of goods longitudinally of said table, a rod transversely mounted of said table, a platform extending longitudinally of said table and adjustably mounted on said rod, a cutter foot mounted on the bottom of said 65 platform and resting on said table, a cutter disc rotatively mounted above said cutter foot, an electric motor mounted on said platform, and a transmission from said motor to said cutter disc, said cutter foot having a flat bottom portion for resting on said table, and a vertical thin back portion connecting with said bottom portion for supporting same, and a bracket mounted on the bottom of said platform for supporting said cutter foot.
- 70 6. An automatic splitting machine, comprising a table, means for guiding a web of goods longi-

tudinally of said table, a rod transversely mounted of said table, a platform extending longitudinally of said table and adjustably mounted on said rod, a cutter foot mounted on the bottom of said platform and resting on said table, a cutter disc rotatively mounted above said cutter foot, an electric motor mounted on said platform, a transmission from said motor to said cutter disc, a shaft for said cutter disc, ball bearings for rotatively supporting said shaft and located at the sides of said cutter disc, tubes for supporting said ball bearings, a bracket mounted beneath said platform, and fastening elements releasably securing said tubes to said bracket.

7. An automatic splitting machine, comprising a table, means for guiding a web of goods longitudinally of said table, a rod transversely mounted of said table, a platform extending longitudinally of said table and adjustably mounted on said rod, a cutter foot mounted on the bottom of said platform and resting on said table, a cutter

disc rotatively mounted above said cutter foot, an electric motor mounted on said platform, a transmission from said motor to said cutter disc, a shaft for said cutter disc, ball bearings for rotatively supporting said shaft and located at the sides of said cutter disc, tubes for supporting said ball bearings, a bracket mounted beneath said platform, and fastening elements releasably securing said tubes to said bracket, and said transmission comprising a pulley and belt transmission system between said shaft and said electric motor.
